PROJECTION SYSTEM

Frank E. Weller, Bloomfield, N. J., assignor to
Trans-Lux Corporation, a corporation of Delaware

Application March 1, 1930, Serial No. 432,328

24 Claims. (Cl. 88—24)

This invention relates to a system for projecting images of printed news matter and the like. One of the objects of the invention involves the provision of a practical and efficient system of this type capable of projecting images of printed matter and the like with a high light intensity. Another object of the invention involves the provision of a simple projection system which may be conveniently and efficiently operated with a Dow-Jones ticker or similar news tickers, or equivalent, and it shall be understood that references in the appended claims to the "printing" of characters is to be considered generically descriptive of the production of characters by any of said tickers, or equivalent devices. Various further objects, features and advantages will appear in considering the drawings forming part of this application and the accompanying detailed description thereof.

In the drawings, Fig. 1 is a sectional side elevation of an apparatus embodying my invention;

Fig. 2 is a plan view thereof;

Fig. 3 is a front elevation taken from the left in Fig. 1;

Fig. 4 is a fragmentary enlarged detail view of the web flattening device employed to keep the web flat in crossing the projection aperture;

Fig. 5 is an enlarged fragmentary detail view showing another form of web flattening device; and

Fig. 6 is an enlarged detail perspective view of the device shown in Fig. 5.

The numeral 1 represents a web or tape which is preferably a thin transparent or translucent flexible sheet of Cellophane or like material. Instead of Cellophane, I may employ glaccine paper which is not quite so expensive as the Cellophane but it is not capable of transmitting the light as well as Cellophane; consequently, with glaccine paper, the light intensity on the screen is somewhat diminished. Giaccine paper has the advantage, however, that strips thereof may be preserved as records and the printed characters thereon easily read when that becomes necessary.

This translucent web 1 is to receive lines of printing, for example, in the usual manner that such lines are provided by a Dow-Jones ticker or like device. I have shown a somewhat diagrammatic form of this ticker in the figures of the drawings and have designated it by the numeral 2. The well-known form of this ticker employs a printing wheel or roll 3 mounted on a shaft 4, the wheel 3 being reciprocated back and forth across the web 1 and, while being moved from left to right, Fig. 3, printing letters or other char-

acters on the web in the usual manner. At the conclusion of the printing of one line, the printing wheel is moved back across the width of the web to initial position at the left side thereof, Fig. 3. At the same time the web is moved along a distance sufficient to allow a proper space between the line just completed and the line to be printed underneath it. The arrangement for this web feed as employed in the usual Dow-Jones ticker has been modified as described below, but the source of power and the connections leading up to the first beveled gear 5 of the web-feeding device is preferably the same as employed in the usual Dow-Jones ticker and is not shown herein. The mechanism which is not shown herein may be seen by reference to the co-pending application of Frank E. Halloran, Ser. No. 453,121 filed May 17, 1930. The connections for operating the printing wheel may also be seen by reference to the co-pending application just mentioned.

On the shaft 4 is the beveled gear 5 meshing with a second beveled gear 6 supported on the end of a short vertical shaft 7 held by brackets 8 on a substantially rectangular vertical frame 9. Mounted on the opposite end of the vertical shaft 7 is another beveled gear 10 mounted to mesh with a beveled gear 11. The latter is attached to the end of a horizontal shaft 12 set practically at right angles to the shaft 7, which horizontal shaft is supported at 13 and 14 on frame 9 near either end thereof. Positioned on this horizontal shaft and spaced a short distance from either end thereof is a pair of knurled rollers 15, 16 (see Fig. 2). These knurled rollers are on the side 35 of the web towards the lamp as will be described later. Rollers 17 and 18 are supported, respectively, by arms 19 and 20 which in turn are supported on a horizontal shaft 21 adjacent the opposite ends thereof, the end of each arm being 40 a sleeve surrounding the shaft 21. These sleeves are engaged, respectively, by helical springs 22 and 23 whereby the roller 17 is biased toward the roller 16 and the roller 18 is biased toward the roller 15. The helical springs are wound around the shaft 21 and act upon the arms 19 and 20 thereby holding the rollers 17 and 18 against the web 1 and pressing this web tightly against the knurled rollers 16 and 15. Upon rotation of the shaft 12 the knurled rollers 16 and 15 rotate and the web being pressed thereagainst by the rollers 17 and 18 is fed vertically therebetween, Fig. 1. This vertical feed causes the web, after leaving the printing wheel 3, as it does each time the printing wheel has finished

scribed below, to move vertically across the frame 9 so that light passing through an aperture in this frame will cause images of the printed matter to be projected to a screen for observation by spectators.

The projecting means for passing light rays through the Cellophane or other web on which the printed matter appears is housed in an aluminum or other casing 24 which is in the form of a substantially oblong box or head with a narrowed throat portion forming the lower part thereof. This casing is supported by an upright pedestal 25. The casing and its support, the ticker and the other parts of the projecting and reflecting system, including mirrors, will be described later and may all conveniently be placed in a cabinet similar to that described in the pending application of Edward H. Unkles, Ser. No. 325,551, filed Dec. 12, 1928.

The projecting means comprises preferably a single incandescent lamp 26 provided with a reflector 27 therebehind supported on the wall of the casing 24 and projecting light through a first condensing lens 28 and then through a second condensing lens 29 cut off to the extent of about one-quarter of its height. The lamp is supported in a conventional socket seated in the throat of the casing 24 and the lens 28 is mounted on suitable supports on the side walls of this casing. The lens 29 occupies an aperture in the front wall of the casing 24 and is also supported by brackets extending from the side wall thereof.

The frame 9 is mounted on the upper part of the housing for the ticker 2 and the ticker is swung so that the frame 9 nearly abuts the lens 29. The frame 9 defines a rectangular aperture 30 through which the light rays from the lamp pass, this aperture allowing the light rays to project a rectangular field upon which images of matter printed on the web appear.

It is important that the web 1 as it passes across the aperture 30 shall be tightly held with its edges flattened against the face of the frame 9. For this purpose I have provided as shown more clearly in Fig. 3, a pair of rollers 31 and 32 held by arms 33 and 34, respectively, which arms are supported by brackets 35 and 36, respectively. The arms 33 and 34 each have extending therethrough a pin 37 which is surrounded by a coil spring 38 arranged to so bias the arms that the rollers 31 and 32 press against that face of the web 1 toward the lamp 26 is pressed by these rollers 31 and 32 against the adjacent face of the frame 9 and the web is thus kept in distended tight flattened condition as it passes across the aperture 30. By passing the web in this flattened condition across the aperture, it results that the images are so projected that they appear finally on the screen without blurring. The rollers 31 and 32 are preferably provided with peripheral faces of rubber 39 which aids them in gripping the web and holding it flat against the frame 9. This is particularly desirable where Cellophane is used as this is a glossy and slippery form of material. It is not necessary to use these rollers with glaccine paper although of course they may be used with this latter, if desired. Instead of the rollers 31 and 32, a form of spring 40 shown in Figs. 5 and 6 may be employed. This spring 40 is also supported on the frame 9 and is somewhat in the form of a U, one end being mounted on a vertical bar 41 attached to the frame 9 and engaged by screws 42 around which the end of the

spring 40 is wound, the other end of the spring 40 being in the form of a loop to press the web 1 against the frame 9. One of these springs 40 is provided on either side of the frame and a section of each projects obliquely of the web 1 and lies against the face thereof away from the lamp 26, the rear face being pressed against the frame 9. Whichever of the devices, just discussed, the rollers or the springs, are used, they are placed near the lower part of the frame so that as the web passes the aperture 30 it has a support on the one hand by these flattening devices at the bottom of the aperture and is supported between the driving and pressing rolls 15, 16, 17 and 18 near the upper part of the aperture.

The light beam passing through the printed web 1 is received by a mirror 44 angularly set so that it will receive all of the light passing through the web and will throw the light beam upwardly through an objective lens 45 which is carried by a U-shaped member 45a, Fig. 2, pivoted on a rod 46 supported in opposite side walls of the casing 24. The member 45a comprises a pair of downwardly inclined arms 45b to which the aforesaid mirror 44 is secured. The member 45a, the objective lens 45 and the mirror 44 are shown in Fig. 1 in normal operating position, further counter-clockwise movement thereof, Fig. 1, about the pivot rod 46 being prevented by a suitable stop arrangement which, as herein shown, comprises lugs 46a, 46a, Fig. 2, projecting laterally from opposite walls of the casing 24 for supporting said member 45a.

The member 45a, objective lens 45 and mirror 35 44 are movable together as a unit. Accordingly, when it becomes necessary to thread the web 1 into projecting position, the above recited parts may be swung in a clockwise direction, Fig. 1, about the pivot rod 46 whereupon said web 1 40 may be placed in projecting position, that is, between the frame 9 and the rollers 31 and 32, and between the pairs of rollers 15, 18 and 16, 17. After the web 1 is thus placed in projecting position, the member 45a may be returned to its 45 position shown on the drawings whereby the objective lens 45 and mirror 44 are returned to their proper projecting positions, respectively.

The mirror or mirrors preferably employed beyond the objective lens 45 are not shown as they 50 may be of any usual and well known type. The light after leaving the last mirror of the mirror system passes directly on to and through a screen, not shown, but which may be as shown in the application of Unkles mentioned above. 55 Upon this screen the images of the printed web characters may be viewed by the spectators.

After leaving the aperture 30, the tape 1 passes vertically upwards to a runway which is preferably of metal and constitutes a top for the casing 24. This runway for convenience in mounting is made in two sections 47 and 48, the top of the runway 49 being preferably sloped from the end on to which the web first comes towards the end from which the web leaves. The web 60 spills down over this latter end and the weight of the accumulated web tends to keep the web passing over the runway flat against the runway. The heat waves developed by the lamp 26 pass upwardly under the surface of runway 49 65 and, as a result, the wet ink on the web is dried. It usually requires about five to ten minutes for a given section of the web to pass entirely over this runway so that there is ample opportunity for drying. When collected after leaving the 70 runway it may be handled without fear of 75

smudging due to undried condition of the printing fluid. This is important in connection with hard surface web such as Cellophane and glaciene paper since they do not readily absorb the printing ink and if not dried, may be easily smudged in the handling so that the record thereon is impaired. A door 50 is provided in the casing 24 which may be opened to allow heat to pass therethrough if the device becomes too hot from continuous operation.

The operation of the apparatus should be obvious and clear from the description given. To briefly summarize it, however, the web 1 is fed by the web-feeding system 15, 16, 17, 18 past the aperture 30. The feeding is intermittent and occurs when the printing roller has reached the end of a line traveling across the web. At that time the roller 5 is actuated to drive the shafts 7 and 12. Shaft 12 causes the web-feeding means 15, 16, 17, and 18 to operate sufficiently to move the web vertically so that the printing roller may then proceed with the printing of the next line. In so doing, of course, the uppermost line of printed matter which has been in the field framed by the frame 9, is moved out of this field and a new line of reading matter is brought into the field at the lower part of the frame. The field framed by frame 9 together with the web section defined thereby is traversed by a beam of light from lamp 26 and lens system 28 and 29, the light beam then engaging the mirror 44, thereafter passing through the objective lens 45 and then coating with one or more mirrors before engaging the screen. The web after leaving the projection field gradually passes over the runway 49 and then drops by gravity to a place where it may be collected, cut up into sections and hung up as a record to be read if desired.

The apparatus is a simple and efficient one. Projection of light through the transparent web permits a high light intensity on the screen and this can be done with the use of a single bulb. The installation cost and maintenance cost of the apparatus is such as to make it practical. The parts involved in the apparatus can be easily gotten at for replacement or repair, while the device is compact and may be placed in a broker's office or other desired location without taking up much space.

While I have described my improvements in detail and with respect to preferred forms thereof, I do not desire to be limited to such details or forms, since many changes and modifications may be made without departing from the spirit and scope of the invention in its broader aspects. Hence I desire to cover all modifications and forms coming within the language or scope of any one or more of the appended claims.

What is claimed and desired to secure by Letters Patent is:

1. In a projection system, a web to receive printing in lines, a printing roll for printing lines transversely of said web, means for moving said printing roll to reciprocate across said web, a frame providing a projection aperture across which said web passes, and feeding rollers mounted in pairs on said frame and arranged to receive the respective opposite sides of said web therebetween to cause the feeding of said web after the printing roll has reached the end of its line of printing.

2. In a projection system, a web to receive printing in lines, a printing roll for printing lines transversely of said web, means for moving said printing roll to reciprocate across said web, a

frame providing a projection aperture across which said web passes, a shaft having feeding rollers mounted on said frame for moving said web across said aperture, said rollers being adapted to contact with one side of said web, resiliently held rollers contacting with the other side of said web and mounted on said frame to press said web against said feed rollers, and connections between said feed rollers and a source of power for driving said rollers.

3. In a projection system, a web to receive printing in transverse lines, a printing roll for printing lines transversely of said web, a frame providing an aperture across which said web passes, projecting means including a source of light for projecting images from said web on to a screen, a housing for said projecting means and providing a downwardly slanting runway for said web to allow heat from said source of light to heat said web through said runway to cause drying thereof, and web-feeding means for moving the web past said aperture and on to said runway, whereupon said web after drying passes by gravity to a place where it is collected.

4. In a projection system, a web to receive printing in transverse lines, a printing roll for printing lines transversely of said web, a frame providing a projection aperture across which said web passes, web-feeding means operating to move said web across said aperture, and a resilient device on each side of the lower part of said frame for pressing the edges of said web against said frame to hold it in flattened condition while it passes said aperture, said web-feeding means and the resilient devices being positioned on opposite sides of said projection aperture.

5. In a projection system, a web to receive printing in transverse lines, a printing roll for printing lines transversely of said web, a frame providing a projection aperture across which said web passes, web-feeding means operating to move said web across said aperture, and an obliquely positioned spring-held roller on each side of the lower part of said frame for pressing the edges of said web against said frame to hold it in flattened condition while it passes said aperture, said web-feeding means and the spring-held rollers being positioned on opposite sides of said projection aperture.

6. In a projection system, a web to receive lines of printing, a printing roll for printing lines transversely of said web, a shaft for said printing roll and operated from a source of power, a web-feeding shaft having feed rollers thereon contacting with the web on one side, spring-held rollers contacting with the web on the other side thereof to move the web toward said feed rollers, projecting means comprising a lamp and a series of lenses, a frame having an aperture, a casing covering the projecting means, a pair of spring-pressed rollers positioned near the lower side of said frame and in front thereof pressing diagonally across the opposite edges of said web to keep the web stretched and flat, and a drying device over the top of said casing to dry the printing on said web and to pass it along to be collected.

7. In combination, means for printing characters on a tape with ink, means forming a projection aperture with respect to and by which said tape is moved, a source of heat, and a support traversed by said tape after passage beyond said projection aperture, said support being in the direct field of heat radiated from said

source of heat whereby drying of the ink on the tape is facilitated.

8. In combination, means for printing characters on a tape with ink, said tape being formed from material highly resistant to the penetrating action of ink, means forming a projection aperture with respect to and by which said tape is moved, and means for drying the ink on a section of said tape while removed from said projection aperture.

9. In combination, means for printing characters on a tape with ink, means forming a projection aperture with respect to and by which said tape is moved, a source of light for passing a light beam into engagement with a tape section defined by said projection aperture, and a support traversed by said tape after passage beyond said projection aperture, said support being in the direct field of heat radiated from said source of light whereby drying of the ink on the tape is facilitated.

10. In combination, means for printing characters on a tape with ink, said tape being formed from material highly resistant to the penetrating action of ink, means forming a projection aperture with respect to and by which said tape is moved, a source of light for passing a light beam into engagement with a tape section defined by said projection aperture, and means whereby heat from said source of light dries the ink on a section of said tape while removed from said projection aperture.

11. Projection apparatus comprising a projection field with respect to which a character-bearing tape is movable, coacting roller means engaging opposite sides of said tape for effecting passage of and guiding the tape through said projection field, a mirror for reflecting a light beam emanating from the section of said tape in said projection field, an objective lens traversed by the reflected light beam, a frame carrying said objective lens, and means for movably mounting said frame whereby said objective lens may be moved aside when it becomes necessary to position said tape in said projection apparatus, said frame having a normal position which determines the projection position of said objective lens and said frame being movable without imparting movement to said roller means.

12. Projection apparatus comprising a projection field with respect to which a character-bearing tape is movable, coacting roller means engaging opposite sides of said tape for effecting passage of and guiding the tape through said projection field, a mirror for reflecting a light beam emanating from the section of said tape in said projection field, an objective lens traversed by the reflected light beam, a frame carrying said mirror, and means for movably mounting said frame whereby said mirror may be moved aside when it becomes necessary to position said tape in said projection apparatus, said frame having a normal position which determines the projection position of said mirror and said frame being movable without imparting movement to said roller means.

13. Projection apparatus comprising a projection field with respect to which a character-bearing tape is movable, coacting roller means engaging opposite sides of said tape for effecting passage of and guiding the tape through said projection field, a mirror for reflecting a light beam emanating from the section of said tape in said projection field, an objective lens traversed by the reflected light beam, a frame carrying said

mirror and objective lens, and means for movably mounting said frame whereby said mirror and said objective lens may be moved aside when it becomes necessary to position said tape in said projection apparatus, said frame having a normal position which determines the respective projection positions of said mirror and said objective lens and said frame being movable without imparting movement to said roller means.

14. Projection apparatus comprising a projection field with respect to which a character-bearing tape is movable, coacting roller means engaging opposite sides of said tape for effecting passage of and guiding the tape through said projection field, a mirror for reflecting a light beam emanating from the section of said tape in said projection field, an objective lens traversed by the reflected light beam, a frame carrying said mirror and objective lens, and means for pivotally mounting said frame about a horizontal axis on the lamp housing of said projection apparatus whereby said mirror and said objective lens may be swung aside vertically when it becomes necessary to position said tape in said projection apparatus, said frame having a normal position which determines the respective projection positions of said mirror and objective lens and said frame being movable without imparting movement to said roller means.

15. In combination, means for printing characters on a tape with ink, means forming a projection aperture with respect to and by which said tape is moved, a source of heat, and a support traversed by said tape after passage beyond said projection aperture, said support being in the direct field of heat radiated from said source of heat whereby drying of the ink on the tape is facilitated, the tape, beyond said support, hanging downwardly free from tension and, by action of gravity, serving to progressively advance the tape across said support.

16. The combination with means for printing characters in line form transversely of a broad web, of means for drawing said web through a projection field, said drawing means gripping the web at the respective opposite edges thereof adjacent the respective exit corners of said projection field, and web-retarding means engaging the web and gripping the respective opposite edges thereof adjacent the respective entrance corners of said projection field said web-retarding means being disposed between the printing means and the projection field, said drawing means and said web-retarding means cooperating to produce a relatively flat web section suitable for projection purposes.

17. The combination with means for printing characters in line form transversely of a broad web, of means for drawing said web through a projection field, said drawing means gripping the web at the respective opposite edges thereof adjacent the respective exit corners of said projection field, and web-retarding means engaging the web and gripping the respective opposite edges thereof adjacent the respective entrance corners of said projection field, said web-retarding means being disposed between the printing means and the projection field whereby vibrations imparted to the web by said printing means are largely prevented from entering said projection field, said drawing means and said web-retarding means cooperating to produce a relatively flat web section suitable for projection purposes.

18. The combination with means for printing characters in line form transversely of a broad

web, of means for drawing said web through a projection field, said drawing means gripping the web at the respective opposite edges thereof adjacent the respective exit corners of said projection field, and web-retarding means engaging the web and gripping the respective opposite edges thereof adjacent the respective entrance corners of said projection field, said web-retarding means being disposed between the printing means and the projection field whereby vibrations imparted to the web by said printing means are largely prevented from entering said projection field, said drawing means and said web-retarding means cooperating to produce a relatively flat web section suitable for projection purposes, said web being of transparent or translucent character suitable for through projection and the projection path on opposite sides of said projection field being suitably transparent for the passage of the projecting light beam.

19. The combination with means for printing characters with ink in line form transversely of a broad web, of means for drawing said web through a projection field disposed in substantially a vertical direction, said drawing means gripping the web at the respective opposite edges thereof adjacent the respective exit corners of said projection field, and web-retarding means engaging the web and gripping the respective opposite edges thereof adjacent the respective entrance corners of said projection field, said web-retarding means being disposed between the printing means and the projection field whereby vibrations imparted to the web by said printing means are largely prevented from entering said projection field, said drawing means and said web-retarding means cooperating to produce a relatively flat web section suitable for projection purposes, said web being of transparent or translucent character suitable for through projection and the projection path on opposite sides of said projection field being suitably transparent for the passage of the projecting light beam, said printing means inking the web characters on the side of said web removed from the lamp which produces said projecting light beam.

20. The combination with the light aperture of a projecting machine, of a broad tape, a printer for printing a plurality of lines of printed matter on said tape, said light aperture being disposed at the tape discharge end of said printer, a condensing lens disposed adjacent to said light aperture with a segment cut off adjacent one side of the effective focusing area of said lens to clear said printer and yet permit location of the light aperture directly adjacent to the tape discharge end of the printer, and means for drawing the tape through said light aperture from the tape discharge end of said printer in a direction transverse to the direction of the lines of printed matter.

21. The combination with the light aperture of a projecting machine, of a broad tape, a printer for printing a plurality of lines of printed matter on said tape, said light aperture being disposed at the tape discharge end of said printer, a condensing lens disposed adjacent to said light aperture with a segment cut off adjacent one side of the effective focusing area of said lens to clear said

printer and yet permit location of the light aperture directly adjacent to the tape discharge end of the printer, and means for drawing the tape a line space at a time across said light aperture.

5 22. In combination with the light aperture of a projecting machine, a broad tape, a printer for printing a plurality of lines of printed matter on and thereafter discharging said tape, said light aperture extending approximately in a vertical direction above said printer at the tape discharge end thereof, a condensing lens disposed in line with said light aperture with a segment cut from the lower side of the effective focusing area of said lens, said lower side of the lens being disposed immediately adjacent the tape discharge end of the printer, and means for drawing the tape upwardly through said light aperture from the tape discharge end of said printer in a direction transverse to the direction of the lines of printed matter.

10 23. In combination with the light aperture of a projecting machine having a screen on which light images are to be projected, a broad tape, a printer for printing a plurality of lines of printed matter on and thereafter discharging said tape, said light aperture being disposed adjacent the tape discharge end of said printer, a condensing lens disposed in line with said light aperture and having a segment cut off adjacent one side of the effective focusing area of said lens, said one side of the lens being disposed immediately adjacent the tape discharge end of said printer, means for drawing the tape step-by-step through said light aperture from the tape discharge end of said printer in a direction transverse to the direction of the lines of printed matter and a lamp from which a projecting light beam passes through said condensing lens, the light aperture, the tape section framed thereby and an objective lens, said light beam coacting with the projection screen and causing the display thereon of images of the lines of printed matter.

15 24. In combination with the light aperture of a projecting machine having a screen on which light images are to be projected, a broad tape, a printer for printing a plurality of lines of printed matter on and thereafter discharging said tape, said light aperture extending in a vertical direction above said printer and adjacent the tape discharge end thereof, a condensing lens disposed in line with said light aperture, said lens having a segment cut from the lower side of its effective focusing area, said lower side being disposed immediately adjacent the tape discharge end of the printer, means for drawing the tape upwardly through said light aperture from the tape discharge end of said printer in a direction transverse to the direction of the lines of printed matter, a lamp for passing a projecting light beam horizontally through said condensing lens, the light aperture and the tape section framed thereby, a second condensing lens disposed between said first named condensing lens and said lamp, and a mirror system including an objective lens with which said light beam coacts to cause the display of images of the lines of printed matter on the projection screen.

FRANK E. WELLER.
